US0D1040594S

(12) **United States Design Patent** (10) Patent No.: **US D1,040,594 S**
(45) Date of Patent: ** Sep. 3, 2024

(54) **INDUCTION COOKER**

(71) Applicant: **Shenzhen Typhur Technology Co., Ltd**, Shenzhen (CN)

(72) Inventors: **Shuhong Wang**, Guangdong (CN); **Chengmin Li**, Guangdong (CN); **Haopeng Li**, Guangdong (CN)

(**) Term: **15 Years**

(21) Appl. No.: **35/519,016**

(22) Filed: **Nov. 15, 2022**

(80) **Hague Agreement Data**

Int. Filing Date: **Nov. 15, 2022**

Int. Reg. No.: **DM/226690**

Int. Reg. Date: **Nov. 15, 2022**

Int. Reg. Pub. Date: **Nov. 17, 2023**

(30) **Foreign Application Priority Data**

CLAIM

The ornamental design for a induction cooker, as shown and described.

DESCRIPTION

1. Induction cooker

1.1 : Perspective

1.2 : Perspective

1.3 : Front

1.4 : Back

1.5 : Left

1.6 : Right

1.7 : Top

1.8 : Bottom

The broken lines shown in the drawings are for environmental subject matter that forms no part of the claimed design.

1 Claim, 8 Drawing Sheets
